UNITED STATES PATENT OFFICE

2,426,094

METHOD FOR BUILDING SHIPS

Frederic R. Harris, New York, N. Y., assignor to
 New Jersey Shipbuilding Corporation, Barber,
 N. J., a corporation of New Jersey

Application June 21, 1943, Serial No. 491,722

8 Claims. (Cl. 114—79)

1

This invention relates to improvements in methods of building ships; especially ships of steel adapted to be constructed by the assembly of large sections of the hull and framing.

It is an object of the invention to provide a method of building ships in accordance with which a vessel can be produced by first prefabricating large portions of the exterior of the hull; putting members inside for reinforcing it and dividing off the compartments; and then uniting the portions at a point near the water's edge suitable for launching.

Another object of the invention is to provide a method of producing ships by which the outside metal plating for the hull is set up first, and fixed in the right position, piece by piece, for each section; and the parts to form inside bracing frames and partitions are then added. To accomplish this each plate is put into a fixture of the proper design for each section and bent and forced into shape and place. Each plate is then united to the adjacent plates. The partitions, bracing frames, ribs, etc., for the inside are then easily attached. All the parts are strongly secured together as by welding.

The fore and aft sections, and the intermediate sections are thus readily turned out by a manufacturing process that enables them to be quickly finished. At the launching site, the sections are laid end to end and connected together permanently to make the complete unit.

With these and other objects and advantages, which will appear in the following description, the invention resides in the novel features expressed in the appended claims. The drawings are of course illustrative only, and the details of structure and proceeding can be varied in many respects without departing from the principle of the invention or exceeding its scope and spirit.

On said drawings:

Figure 1 shows the manner of setting up the outside plates and forming the sections according to the contour of the vessel in each part thereof.

Figure 2 presents a detail of construction.

Figures 3 to 10 inclusive show the shapes of various members to be formed and affixed in the sections after the plates have been formed and united to produce the sections.

Figures 11 and 15 illustrate parts of additional frames for the same purpose.

Figure 12 shows diagrammatically two sections of the vessel about to be joined together.

Figure 13 is a side view and illustrates the general contour of the vessel's hull.

Figure 14 presents a fore elevation (left) and an aft elevation (right) showing the outline of the cross-sectional shape of the hull of the vessel at various points in its length, and

2

Figure 16 illustrates a further detail of a part used in forming some of the sections of the vessel.

The same numerals identify the same parts throughout.

In practice, a ship having the shape and contour shown in Figures 13 and 14 is constructed of sections, assembled end to end and welded together, as illustrated in Figure 12. For example, 10 eight sections are constructed, each consisting of an outside shell or plating, and inside stiffening or reinforcing members. Each section is produced and fabricated by first setting up the outside plates in a crib or fixture, which holds them in positions to give the section the precise configuration, lengthwise and crosswise, of that part of the hull which the section is intended to embody; and then butt-welded to connect them one to another. The stiffening and partitioning members are then installed and affixed by welding 20 to the interior of the section, to make a complete structural unit. The union of the sections then follows. In the ensuing description, the construction of one of such sections is illustrated and described in detail, with special reference to Figure 1, all other sections being turned out in the same way, but with the plates at different angles, as the contour of the ship at different points requires. My process is thus the reverse 25 of the conventional way of building a ship by first erecting the frames or ribs and then adding the plates; and therein lies much of its novelty and merit; for by such a mode of proceeding I am enabled to finish and deliver a ship at a great saving in time and expense.

The fixture shown in Figure 1 comprises a number of stringers 21, laid transversely, and at the ends of each stringer are uprights 22. An inclined beam 23 is affixed to the top of each upright and to the stringer below the upright at a point between the upright and the center of said stringer. Another inclined beam 24 is affixed to said stringer near the center and to said beams 22 and 23 between the upper and lower 30 ends of same. The stringers with the upright and inclined beams at the ends are, in this instance, four in number, and laid upon flanged girders or other suitable supports. They make up a cradle or crib to receive side and bottom plates shown at 26 and 26a, 28 and 28a respectively; the former being the side plates of the section and the latter the bottom plates. They are held in position by bolts 25 mounted in the beams 23 and 24. The line where the side plates meet the bottom plates marks the chine 29 on each side of the ship. The bolts are passed through the beams 23 and 24 and tack-welded at their ends to the plates, as shown at 30. By means of nuts 31 and washers 32 bearing against 35 the beams, the bolts can be taken up to pull

upon the plates and force them to assume the required shape.

With a fixture like this the plates can be bent out of a single plane and give a surface having the curvature and configuration of any part of the ship. Plates 26 and 26a are so worked, and then welded to the plates 28 and 28a and to each other. The plates 28 and 28a are also welded together along their lower edges. Butt seams are preferred. The plates which meet to make cross seams will have lugs 33 for bolts to draw them together and make them abut fully and smoothly along their adjacent edges.

The ship sections made in this way will have curved surfaces because the plates will be so formed by the bolts 25. The inclined beams 23 and 24 will be set at varying angles for this result.

The left half of Figure 14 shows a fore elevation of the hull and the right half an aft elevation. The inclined lines marked 1 to 19 at the top correspond in position to vertical lines bearing the same numbers in Figure 13; that is they mark transverse planes and the outline of the hull in each of them. Thus, the line 1 and its continuation at 1a below the chine 29 to the keel show the slant of the starboard side and bottom near the bow; the lines 10, 11, 12 and 13 show the cross-sectional shape of the hull amidships and every other line also is such an indication. The inclination of the beams 23 and 24 is determined by the slant of these lines above and below the chine 29. Thus, in Figure 1, the beams 23 and 24 on the four stringers have approximately the slope of the lines 2, 3, 4 and 5, and 2a, 3a, 4a and 5a respectively, below them, and the section of Figure 1 is therefore the second one, or immediately after the bow, and contains reinforcing members from 14 to 27-inclusive. The other sections are formed by inclining the beams 23 and 24 according to the other lines in Figure 14. At some points, the vertical beams 23 might be omitted and low triangular plates mounted on the stringers instead of the beams 24. Lines a—b and c—d show the shape of the bow and stern of the ship.

Inside of each section transverse reinforcing members in the form of fabricated frames or bulkheads will be formed and installed and welded to the plates. An example of the frames for the section of Figure 1 is illustrated in Figure 4; and there will of course be several frames in each section. In Figure 13 I indicate by vertical lines numbered from 1 to 19 along the bottom, the position of every fifth reinforcing member (frame or bulkhead) in the finished hull, which thus comprises 100 in all. This number can of course be altered.

The hull illustrated in Figure 13 includes eight sections but the number can be larger or smaller. The first or bow section contains the first 13 reinforcing members; the second contains the 14th to the 27th inclusive; the next the 28th to the 42nd; the fourth, the reinforcing members beginning with the 43rd and ending with the 57th. The fifth ranges over the 58th to the 67th; the sixth from the 68th to the 80th; the seventh from the 81st to the 91st; and the last includes the remainder and constitutes the stern section. The 12th reinforcing member is a bulkhead; likewise the 27th, 42nd, 57th, 67th, 81st, 90th and 96th, as indicated along the top of Figure 1; all the others being open frames.

The section of Figure 1 will, when finished and ready to be united to the bow section, contain the

reinforcement running from the 14th to the 27th. The method of joining the sections is shown in Figure 12. The bow section B after being formed and receiving twelve frames and the first bulkhead is cut free from the ends of the forming bolts 25, as with a torch, and is transferred to a cradle or platform. The next section B' is transferred to the same platform and the ends of the two are then drawn together by bolts 34 engaging the lugs 33 or similar devices and connected by turn buckles. When the edges of the two sections meet they are welded together. The exact positions of the seams and butts, that is, the length of the different sections, is determined by the requirements of design and construction. For the sake of clearness only two reinforcing members, one bulkhead and one frame, are shown in Figure 12, but it will be understood that each section contains many more.

20 The various frames are given shape according to the designed cross section of the hull at various points. A few such frames are presented by way of example. The various frames and other reinforcing members for the interior of the ship are depicted in the drawings as they would appear if set up as fully finished, separate units. They are not, however, so produced; but are put into position, piece by piece, and welded fast. Some of the views also show parts that really do not belong to the frames, but are only attached to them at one point or another. Figure 3 shows the half of the frame which will have the fifth position in the bow section; marked by the vertical dot-and-dash line 1 in Figure 13. It is made up of a lower angle bar 37 and an upper 38 at each side, joined at the location of the chine 29. A gusset 39 unites each bar 38 to the deck-supporting angle beam or rib 40. At 44 I indicate a central longitudinal reinforcing I-beam, which will be welded to other members of the kind and the rib 40 when the sections are joined to make a continuous beam extending the full length of the hull. This frame also includes a floor or platform-supporting angle beam 41, attached to central angle-bars, props or struts 43. A gusset 39' joins the lower end of each bar 43 to the adjacent bar or rib 37. The keel will be in the longitudinal plane of the braces 43 and rib 44.

In Figure 4 I illustrate half of a web frame 50 to occupy the 20th position, marked by the vertical line 4 on Figure 13. This frame comprises bottom webs or plating 37a, affixed at the outer ends to inclined angle-beams 38a for the sides of the hull. The deck beam is shown at 40a' and is joined at the middle and near its outer ends to the plating 37a by posts 45. These posts are secured by gussets 46. Vertical metal stiffening bars 47, T-shaped in cross section, are attached to the face of the plating 37a. This member also 55 serves to support a platform on its upper edge in the hull, and as a partition for the space below it. The hull, at the point where this frame is installed is wide enough to require longitudinal deck beams 44 at the top of all three posts 45.

The frames of Figures 5 and 6 are for the 36th and 66th positions, near the vertical lines 7 and 13 in Figure 13. They are made up respectively of bottom beams and side beams 37b and 37c, 38b and 38c joined together at the chine position 28 by gussets 39. The deck supports are shown at 40b and 40c, extending across the three longitudinal deck stringers 44. Platform supporting angle-beams 41b and 41c extend across from one side beam to the other, and are braced by posts 70 at each side of the center and two side posts 43b.

and 43c, uniting the horizontal members 41b and 41c to the bottom beams. The central posts are affixed to the bottom beams by gussets 48b and 48c.

The 82nd frame, placed near the line 16 in Figure 13, will be made similar in shape to the frame of Figure 6, but of less height.

Figures 7, 9 and 10 show the framework for the midship part of the hull, marked by the vertical lines, say, from 10 to 13 on Figure 13. Figure 7 presents a bulkhead consisting of an upper web or plating 49 and lower plating 49d, reinforced by perpendicular stiffeners 50d, and separated by the plating of the inner deck or platform 51. This platform also rests on a longitudinal bulkhead 58, which may extend the full length (or less) of the ship, and also be set up in each of the hull sections, welded in place along top and bottom and at the ends. It may run between the posts 43 (Figure 3), the partitions 37a (Figure 4) and the center posts 43b and 43c of Figures 5 and 6. Bulkheads of this and a different shape are affixed within the sections so as to be in the 12th, 27th, 42nd, 57th, 67th, 81st, 90th and 96th positions in the assembled hull, and extend from bottom to deck. Below the platform 51 there will be transverse partitions in the 7th, 20th, 35th, 50th, 62nd, and 86th positions also to divide the bottom space into compartments. The sections of the longitudinal bulkhead are not parts of the frames but are set into the hull sections separately along the keel and welded in place. In some places under the platform, additional partitions or small bulkheads 59 may also be installed lengthwise to divide the bottom space into more compartments.

Figure 8 shows the type of frame set up just aft of the midship section, say, from positions 67 to 81. It embraces bottom beams 37d united to slanting side beams 38d. The transverse deck beams appear at 40d, shortened between the longitudinal beams 44 to give space for a hatch. Rigid with the beam 38d is a gusset 41d for the transverse, horizontal platform beam; and the bottom beams 37d are connected by gussets 48d, to be joined to the longitudinal bulkhead or keel section 58d.

Figure 9 shows a web frame in part and Figure 10 similarly an open frame for the midship section. The former has a web or plating 49e below the platform with vertical stiffening ribs 50e, to be joined in the hull to the longitudinal bulkhead 58 and partition 59'. The chines 29 are at the lower outer corners of the webs 49e. To each upper corner is welded a side beam 38e, to the upper end of which is joined the deck beam 40e. Posts 45 at center and sides extend from platform to deck beam, secured at their ends by gussets 46. The open frame of Figure 10 (without web) has bottom beams 37f, side beams 38f, deck beams 40f, platform beams 41f, and supporting braces 43f therefor at sides and center, the center posts being duplicated if desired to receive the longitudinal bulkhead between, and attached to the bottom beams by gussets 48f.

Figures 7, 8, 9 and 10 show further the bottom, side and deck plates 52, 53 and 54 respectively, with angle bars 55 along the junction of deck and side plates, and angle-shaped chine bars 56, bent as required. The various bars may have any desired cross section.

Beginning just aft of the transverse plane marked by the vertical line 16 in Figure 13 the

hull is shaped to have a central tunnel under the stern for propellers and rudders. This tunnel is shown at 59 (Figures 13 and 14) and it rises above the chines 29. The shape of the part of the hull with the tunnel is indicated by the elevation forming the right of Figure 14, and the frames of Figures 11 and 15, also by Figure 16. The tunnel begins about at the position marked by the vertical line 17 in Figure 13, is highest at the line 19, and then tapers out till the bottom across the full width thereof coincides with the chines again at the stern of the ship.

The stern section extending from the line 90 aft is formed in a fixture or cradle which as compared with that shown in Figure 1 has the stringers 21 and beams 24 omitted, and beams 23 nearby perpendicular. See lines 17 and 17a in Figure 14. On the supports not shown, for the stringers 21, and between the inclined beams 23 I set upright upon their longest edges plates having the shape of an isosceles trapezoid such as indicated at 63 in Figure 16. On Figure 11, for instance, the top and one end of such a trapezoid will correspond with the bottom edges 60 and 61. The plates 63 at the positions indicated by the vertical lines 17, 18 and 19 in Figures 13 and 14 will have a height equal to the distance from the horizontal lines 17a, 18a and 19a in Figure 14 to the horizontal lines 17b, 18b and 19b respectively, while the positions of the three supports for such plates is indicated by the lines 17a, 18a and 19a. The outside plating for the hull is then laid on the upper edges of the plates 63, on their inclined side edges, on the tops of the supports for these plates from the plates 63 to the beams 23, and against the beams 23; and all welded together along their edges. Thus, the hull gets such a cross section that parts of the frames of the type shown in Figures 11 and 15 will fit the inside of the stern section, with the tunnel 59 therein. The lower edge 62 of one part 64 (Figure 11) will be welded to the bottom plates at the level of the chines 29, the edges 61 to the side plates of the tunnel and the edges 62 to the plates of the top of the tunnel.

The tunnel frame of Figure 11 will be set up in the 92nd position in the hull. It comprises inclined side beams 38g, fixed at the lower end to plates 64, having the aforesaid edges 61 and 62, and each attached to a bottom beam 37g, to be affixed to the longitudinal bulkhead section 58g by a gusset 48g. The deck beams and longitudinal I-beams 44 are also put in at this part of the ship, but are not shown in Figures 11 and 15.

The frame of Figure 15 intended for the 97th position in the hull just aft of the vertical line 19 on Figure 13, comprises a web or plate 63h at the bottom, joined to the side beams 38h at its outer ends. The deck beams are indicated at 40h and the web is reinforced by vertical stiffening ribs 50h. The lower reentrant edge of the web 64h has the edges 60h, 61h and 62h to be welded to the tunnel top side, and bottom plates on the inside of the stern section. The tunnel will be highest in the vertical transverse plane of the line 19 on Figure 13, as represented by the vertical distance between the lines 19a and 19b in Figure 14.

Thus every section from stem to stern is produced by connecting the plates to form the shell or skin, and affixing the reinforcing members to the inside thereof. The sections are then connected together by welding as shown and de-

scribed with reference to Figure 12. A ship built in the manner above described can be completed by adding deck houses, galleys, hatches, bulwarks, etc., and supplying and installing all necessary equipment in the hull at places appointed to receive each item or unit.

The sections built up in the fixtures need not necessarily be of the full width of the hull. In some instances they may be of less width, but produced and joined together according to the general plan above described.

Having described the preferred mode of proceeding, what I believe to constitute my invention is:

1. The method of building ships which consists in setting up in a fixture plates for the outside of the hull of the ship, bending and connecting said plates while in said fixture to give them the shape required by the exterior contour of the hull, and affixing parts forming reinforcing members to the inside of said plates after connecting the latter.

2. The method of building ships which consists in bending plates in a fixture and connecting said plates in said fixture to form separately the outside of several sections to make up the hull, setting up parts forming reinforcing members for the hull in each of said sections, and uniting said sections, with the members therein, together to complete the hull.

3. The method of building ships which consists in setting up in fixtures plates to form separately several sections to make the hull of the ship, bending said plates in each fixture according to the contour of the respective parts of the hull embodied in said sections, connecting each plate to the adjacent plates in each section, setting up parts forming reinforcing members in each section and fixing the said parts in place therein, and uniting the sections end to end, with the members therein, to form the ship.

4. The method of building in separate sections the hulls of ships consisting in setting up in a fixture plates to form each section of the hull of a ship, tack-welding said plates to bolts in said fixture, taking up on said bolts to bend said plates into the required form in said fixture, welding said plates to one another at their edges, and securing parts forming stiffening members in said sections to said plates.

5. The method of building in separate sections

the hulls of ships consisting in setting up in a fixture plates to form each section of the hull of a ship, tack-welding said plates to bolts in said fixture, taking up on said bolts to bend the plates in said fixture into the form required by the configuration of the ship, attaching parts forming reinforcing members in each section to said plates, and uniting said sections end to end in proper position.

10 6. The method of building ships according to claim 4, wherein said ships have longitudinal tunnels under the stern portion, and forming the stern section in fixtures conforming to the cross section of the stern portion.

15 7. The method of building ships consisting in setting up and bending plates in a fixture to form the outside of sections of the hull, said sections having the full width thereof, forcing the edges of the plates together at the seams crossing the hull, welding all the plates together along their edges in said fixture, installing and affixing parts constituting reinforcing members inside of each section, bringing said sections into alignment, forcing them together along their transverse

20 25 edges and permanently connecting said sections to one another along said edges.

25 8. The method of building a ship hull comprising the steps of bending members which are to form the outer skin of the hull to the shape of

30 35 the hull against the inner surfaces of a jig, said inner surfaces defining the shape of the hull, connecting said members together while in said jig after they have been bent to said shape, and thereafter installing reinforcing elements within said skin.

FREDERIC R. HARRIS.
